UNITED STATES PATENT OFFICE.

CHESTER H. THORDARSON, OF CHICAGO, ILLINOIS.

ELECTRICAL TRANSFORMER.

1,288,750.

Specification of Letters Patent.

Patented Dec. 24, 1918.

Application filed July 10, 1915. Serial No. 39,044.

To all whom it may concern:

Be it known that I, CHESTER H. THORDARSON, a citizen of the United States, and a resident of Chicago, in the county of Cook and State of Illinois, have invented certain new and useful Improvements in Electrical Transformers; and I do hereby declare that the following is a full, clear, and exact description thereof, reference being had to the accompanying drawings, and to the characters of reference marked thereon, which form a part of this specification.

This invention relates to certain new and useful improvements in electrical transformers and certain of the improvements are more especially adaptable to the core type of transformers while others are capable of adaptation to other types of transformers.

Among the objects of the invention are to improve, simplify and increase the efficiency of transformers.

A further object of the invention is to provide a transformer the parts of which are made of units which are capable of being readily assembled and, when assembled, produce a rigid, compact and durable structure.

A further object of the invention is to produce a novel magnetic circuit structure for transformers and a novel means of assembling and maintaining the same in assembled relation.

A further object of the invention is to produce a novel construction for maintaining the active and insulating elements of the transformer properly cooled.

Another specific object of the invention is to provide novel means to maintain the cooling medium in circulation.

A further object of the invention is to provide a novel means for connecting the units of a winding where said units are made up of spirally wound sections which are disposed side by side around the core.

A further object of the invention is to provide means for protecting transformer windings, both the high and low tension windings, against excessive overloads or surges which may be thrown on the windings and to thereby prevent burning out of the windings.

Other objects of the invention will appear from the following description and the invention consists in the arrangement and

combination of elements shown in the drawings and hereinafter described and claimed.

In the drawings:

Fig. 1 is a side view of a transformer embodying my invention, with the inclosing casing shown in section.

Fig. 2 is a vertical longitudinal section thereof.

Fig. 3 is an enlarged partial transverse section of the core, the high and low tension windings and the insulating elements associated therewith.

Fig. 4 is a section on the line 4—4 of Fig. 3.

Figs. 5 and 6 are details of the insulating separator member employed between the units of the high tension winding.

Fig. 7 is a diagram illustrating the electrical connections of the low tension winding.

Fig. 8 is a fragmentary detail illustrating a portion of a surge proof device connected to the high tension winding.

Fig. 9 is a detail illustrating one of the units of the high tension winding and a mode of stiffening the winding.

Fig. 10 is a cross section on the line 10—10 of Fig. 9.

Fig. 11 is a detail of the insulating joint between the ends of the inner stiffening turn shown in Fig. 9.

Figs. 12 and 13 are sections taken on the lines 12—12 and 13—13, respectively, of Fig. 1.

Fig. 14 is a cross section of the core, showing a modified means of spacing the low tension winding from the core and for clamping the core laminæ together.

Fig. 15 is a longitudinal section on line 15, 15 of Fig. 14.

As shown in the drawings, 10 designates the inclosing casing of the transformer made of a depth to contain a body of oil or other cooling medium which is circulated through and about the active elements of the transformer. It is provided with the usual removable cover 11, having therein bushings 12 through which the conductors 14 of the high tension winding circuit extend. The mode of leading the low tension winding circuit conductors from the casing is not herein shown but they may be led from the casing in any suitable or convenient manner.

The magnetic circuit of the transformer,

which is of laminated construction with the laminæ parallel to the path of the magnetic flux, consists of a core 15, upright end members 16, 16 and a base member 17. The abutting ends of the end and base members of the circuit structure are beveled and meet along oblique lines disposed, as herein shown, at forty five degrees to the vertical. This construction provides an increased length of contact between the members of the circuit and improves the magnetic joint. In order to hold the end and base members in assembled relation with respect to each other and fixed in the casing, I may provide the end walls of the casing with internal vertical grooves formed between angle bars 18 which are attached to the casing walls to snugly receive the end members, and provide the lower wall of the casing with a like horizontal groove formed between similar angle bars 19 attached to the bottom wall of the casing, said circuit members being suitably insulated from the bars and casing walls. This construction renders it unnecessary to clamp the laminæ together by means of bolts which pierce the same, or otherwise, and affords means whereby the plates constituting the members are confined in proper relation to each other, and also serves to hold the mitered ends of the bottom and end members in fixed relation to each other, the bottom and end guide and confining bars meeting at the lower corners of the casing. The arrangement is such also that the laminæ may be slightly separated so as to permit oil to pass into the spaces between them to thereby aid in cooling, and avoid the formation of eddying currents in this part of, the circuit structure.

The core 15 is arranged at an inclination to the horizontal in order to facilitate the flow of cooling oil along said core and the parts mounted thereon, as will hereinafter more fully appear. In order to afford a convenient means for connecting the core with the said end members 16, and one which lends itself readily to assembling and which produces an efficient interlocking connection between the core and the end members of the circuit, the upper ends of the said end members may be convexly curved to fit downwardly opening concave recesses 20 of the core. The rounded engaging portions of the core and end members increase the area of contact between the laminæ thereof and thereby improve the integrity of the magnetic joint at these points. The rounded joining faces are preferable, though not in all cases essential, for the reason that such a joint admits of greater or less inclination of the core, as desired, while maintaining good magnet joints.

The construction described provides a ready mode for assembling the members of the magnetic circuit and one which avoids

the necessity of bolts piercing the parts at the joints. Moreover, it permits the core and the windings thereon to be readily lifted out of place without disturbing the remainder of the circuit structure.

25 designates, as a whole, the low tension winding of the transformer and 26 designates, as a whole, the high tension winding thereof. Each of the said windings, as herein shown, is made of a series of connected disk-like or slab units each made of a spirally wound flat wire such, for instance, as shown in my co-pending application for U. S. Letters Patent, Serial No. 744,001, filed on the 24th day of January, 1913. With respect to certain features of the invention this type of winding is a preferred, though not essential, one.

The sections or units 28 of the low tension winding are arranged side by side on the core and are separated by a series of angularly spaced radial spacers 29 made of suitable insulating material, as most clearly shown in Figs. 3 and 4. The said spacers are interlocked at their ends with spacer bars 30 which extend longitudinally of the core and winding, the interlocking connection herein shown consisting of undercut or dove-tail grooves in the bars engaged by like projections at the ends of the spacers. This construction is such that the low tension windings and their radial and longitudinal spacers may be assembled as a complete low tension unit of open work or "squirrel cage" formation and may be handled as such unit in the assemblage of the transformer.

The low tension winding is shown in Figs. 3 and 4 as mounted on a cylindric insulating sleeve or taping 32 which surrounds the core 15 and, as shown in the latter figures, is supported on said core by means of longitudinal insulating slabs 33 which are flat at their inner sides and engage the flat sides of the core and are rounded at their outer sides so that the assembled sets of slabs constitute a cylindric inner support for said sleeve 33. The inner spacer bars 30 rest against said insulating sleeve 32 and form between the low tension winding and sleeve longitudinal spaces or channels 36 through which a cooling medium may be circulated. The radial separators 29 also provide radial channels 37 (Fig. 2) between the winding units outwardly through which a cooling medium may be directed.

In order that the cooling medium may be directed along and in contact with the sides of the core, the insulating slabs 33 may be provided at their inner flat sides with longitudinally arranged conduits or channels 38, as shown most clearly in Fig. 3. The said channels 38 are open at their ends to the oil, or other cooling medium space of the casing, as best shown in Fig. 1, whereby a free

circulation of the cooling medium through the said channels 38 from end to end of the core is afforded.

The winding units 40 of the high tension winding surround the low tension winding and are arranged side by side. They are spaced from each other by means of angularly separated, radial-insulating spacers 41 to provide between said units radial passages or conduits to direct a cooling medium between the units. The said spacers 41 are interlocked at their ends with longitudinal spacer bars 43 in the same manner as the spacers 29 and the spacer bars 30, before described, are interlocked. The high tension winding units and said radial and longitudinal spacers may be assembled as a complete unit of open work or "squirrel cage" type and so handled in assembling the parts 20 of the transformer.

The high tension winding is separated from the low tension winding by insulating sleeves or shells 44, 45. The longitudinally arranged spacer bars 43 at the inner ends of the radial spacers 41 of the high tension winding rest upon the outer insulating shell so as to form between said shell and high tension winding longitudinal channels or conduits 46 for a cooling medium. Likewise, the outermost spacer bars 30 of the low tension winding engage the inner insulating shell 45 so as to form between said shell and the low tension winding other cooling medium conduits or channels 49. The two insulating shells 44, 45 are likewise separated by a series of longitudinally arranged, angularly spaced spacer bars 50 (one of which is shown in Fig. 3) which provides another series of longitudinal channels or conduits 40 for the circulation of a cooling medium.

Preferably, and as herein shown, the extended interlocking ends of the spacers 41 and 29 do not extend entirely to the bottoms of the undercut grooves of the spacer bars 43 and 30, respectively, so as to thereby provide at the bottoms of said grooves longitudinal conduits 52 through which a cooling medium may be conducted.

The inclination of the core 15 is an advantageous arrangement in connection with the several longitudinal channels or conduits for cooling medium formed between the active and insulating elements of the transformer, as such inclination of the core 55 gives a like inclination to each of the longitudinal conduits or channels downwardly through which the cooling medium may flow by gravity. Thereby an efficient circulation of the cooling medium is effected. The 60 tendency of the heated cooling medium to rise has the effect to carry it upwardly through the several transverse or radial passages or conduits between the units of the high and low tension windings. Thus it

will appear that the gravity controlled circulation of the cooling medium, due to the inclined core and parts thereon, co-operates directly with the arrangement of the radial or transverse conduits between winding units to facilitate the circulation of the cooling medium around all the active elements of the transformer.

This arrangement of the radial or transverse passages between the winding units, made of spirally wound flat wires insulated by insulating strips, as set forth in my aforesaid co-pending application, whereby the edge of each turn of each winding is bared for contact with the circulating cooling medium, is of great importance inasmuch as the oil flows freely past each edge of each turn so that interchange of heat from the wires to the cooling medium is greatly enhanced.

The arrangement of the two insulating shells 44, 45 between the high and low tension windings is of considerable importance in coils operating under very high tension, inasmuch as the insulating barrier between the coils is thereby greatly augmented. The arrangement herein shown, whereby the two shells are separated by spacer members 50 to form a cooling medium conduit between the same, further increases the break-down point between the high and low tension windings by reason of the fact that each shell is exposed to the influence of the cooling medium on both its inner and outer sides, whereby said shells are protected from temperature break-down.

The outer shell 44, or that nearest adjacent to the high tension winding, is but slightly longer than the said high tension winding. The inner shell 45 is considerably longer than the outer shell, but terminates at its ends short of the end members of the magnetic circuit structure so as to avoid electrostatic leakage along the same to the outer members of said circuit structure.

At one or both ends (both ends as herein shown) of the high tension winding is arranged a surge proof device 55 which is constructed in all essential respects like the surge proof device illustrated in my co-pending application for U. S. Letters Patent, Serial No. 793,787, filed on the 6th day of October, 1913, with the exception that the cross section of the device herein shown is oval instead of cylindric as shown in the aforesaid application. Said surge proof device consists essentially of a series of conductors of progressively increasing cross section, in series with the high tension winding, and between the turns of said conductors are adapted to be arranged one or more resistance elements, as set forth in my aforesaid prior application. As herein shown, the conductors of the surge proof device are

so arranged that the conductors of progressively increasing cross section surround the conductors of lesser cross section. The outermost or greatest cross-section conductor 5 is connected to the adjacent winding unit of the high tension winding by means of a connection 56 (Fig. 4) while the innermost conductor of the surge proof device is adapted to be connected to the external terminal 10 in the manner shown in my aforesaid prior application last above referred to.

As a further improvement, and to protect the high tension winding from the effect of overload or short circuit stresses, the first 15 two or three winding units of the high tension winding adjacent to the surge proof device are made of conductors having progressively decreasing cross section, the unit at the end of the winding having the largest 20 cross section. As herein shown, three of such differential coils 40^a, 40^b, 40^c are employed, with the unit 40^a of the winding having coarse or large cross section, while the conductors of the units 40^b and 40^c are 25 of progressively decreasing cross section. The remainder of the units of the winding may have conductors of uniform cross section. Furthermore, the insulation between the turns of the windings 40^a, 40^b, 40^c are 30 of progressively decreasing thickness, the insulation between the turns of the outermost units being thickest. The employment of the three or more outside winding units having conductors of graded cross section 35 and with the insulation between the turns thereof of progressively decreasing thickness enables the high tension winding, as a whole, to receive greater shocks without injury than if the conductors and the insulation between the turns thereof be of uniform thickness throughout the length of the winding.

As a further and separate improvement in winding units or coils made of spirally 45 wound flat conductors, and in order to mechanically brace the units so that they may be individually handled without danger of collapsing them, and to strengthen them in the assembled transformer, the inner and 50 outer turns 60, 61 thereof are made of relatively massive stiff wire. As herein shown the innermost turns consist of half round cross sections with the flattened sides thereof lying against and in metal-to-metal contact with the adjacent ends of the flat turns. In some instances, said winding units are 55 made principally of flat aluminum wire and the outer and inner stiffening turns of copper. By reason of the fact that it is not practicable to solder the thin, flat wire, constituting the principal part of the winding unit, to the inner and outer stiffening turns, I have herein shown a special method of establishing electrical connection between the

said parts. The present method is shown in 65 Figs. 9, 10 and 11. It consists, at the inner and central parts of the units, of laying on the flat faces of the inner stiffening turns 60 two or more insulated turns of flat wire 62, somewhat heavier than that of the bodies 70 of the units and insulated from each other and lying for a substantial length in metal-to-metal contact with said inner turns, and the inner ends of the flat wires 63 constituting the main bodies of said units overlapping 75 in metal to metal contact the intermediate thickness flat wire, the inner stiffening connecting turns being held assembled by pressure due to the winding of the wire. The inner turns may be fastened together 80 at their ends by means of insulating dowels 64 which enter at their ends sockets formed in the ends of the inner turns, and provided between their ends with flanges 65 which bear against the flat ends of the inner turns 85 to prevent short circuiting about the inner turns.

As an improved means of connecting the adjacent units of the high tension winding the spacer members 41, which extend from the 90 inner to the outer sides of the high tension winding, are provided with slits 57 which extend from end to end thereof and are disposed obliquely of the planes of the spacers, and through these slits connecting conductors 95 58 extend diagonally from the outer turn of each winding unit to the inner turns of the next adjacent winding unit. The leads or connections 58 may be soldered to the inner and outer turns of the units. This 100 mode of connecting the units has the effect of equalizing the stresses between adjacent winding units from the inner to the outer turns thereof. The extension of the connections 58 through the insulating spacer 105 members insulates said connections from the turns of the windings thus connected.

The high tension windings are held from endwise displacement on the outer insulating shell 44 by means of spacing bars 67 110 made of insulating material which extends between the end walls of the casing or parts attached thereto, and insulating members 70 arranged outside of and bearing against the surge proof devices 55.

In order to avoid corona discharges from the salients of the members 16 and 17 of the magnetic circuit structure or of the casing, I may provide shields 72 which cover the upper and inner faces of the members respectively, and are provided with outwardly curved side portions which extend to the casing. A like corona shield 73 may be arranged just within the upper open side of the casing 10 beneath the cover thereof to 120 avoid corona discharges from the terminals 14 and the top edges of the metallic casing 10.

In Fig. 7 is shown a preferred winding

diagram for the low tension winding. As shown in said figure, 75 designates the feed wire and 76 designates the return wire of the low tension circuit. The coils, indicated 5 diagrammatically at 77, are connected in parallel to said feed and return wires. With this arrangement, disturbances set up in the low tension winding, due to surges or shocks in the high tension winding are more nearly 10 equalized than if the said coils of the low tension winding were connected in series, and consequent reaction on the high tension winding is avoided.

As a further improvement each coil or 15 winding unit of the low tension winding is connected through a conductor 79 to the ground so as to thereby enable high tension charges such as are injurious to the winding, to be tapped off to the ground and danger 20 averted.

The said lead and return wires 75, 76, respectively, are carried outwardly from the low tension winding in groups through the space between the low tension winding and 25 the upper side of the core, as shown in Fig. 3. They are insulated from the low tension winding units by insulating shields 78, made of mica or like insulating material.

In Fig. 14 is shown a modified arrangement of insulating the low tension winding from the core. As therein shown, each corner of the core is embraced by a longitudinal plate 80, of substantial W-shape in cross-section, said plates being insulated from the 35 core by insulating sheets 81. The said plates are bound together by tie bolts 82, 83, which may be insulated from the plates by insulating bushings 84 to avoid a closed circuit through said plates around the core. The 40 edges of the plates support the inner longitudinal spacer bars 30 of the low tension winding, said bars being grooved at their inner sides to receive the edges of said plates.

The last described arrangement avoids the 45 necessity of piercing the plates or laminae of the core to bind them together. The cross section of the plates is such as to give great strength thereto, and also provide ample space between the core and the low tension winding for the passage of a cooling medium along said parts to maintain the same properly cooled.

In order to prevent the endwise displacement of the shells 44 and 45 with respect to 55 each other and to the core 15 I may provide anchoring means in the nature of lugs or washers 90, shown in Figs. 1 and 2, which are attached in any suitable manner to braces 67 and, as herein shown, engage the ends 60 of the shells. Inasmuch as said braces are fixed relatively to the frame which carries the magnetic circuit and inasmuch as the lugs or washers are fixedly attached to the braces, this arrangement serves to positively

hold the shells from endwise displacement 65 with respect to the fixed parts.

The surge proof device before referred to, and designated as a whole by 55 serves, in addition to its function of preventing heavy surges coming into the high tension 70 winding, as corona shields to avoid corona discharges between the ends of the high tension winding, along the insulating shells 44 and 45, to the end members of the magnetic circuit or to the frame which supports the 75 same. The presence of the conductor element at the ends of the high tension winding having exteriorly rounded surfaces, such as is presented by the surge proof device referred to, has the effect to equalize the electro-static pressures or stresses along the end 80 faces of the high tension winding and to avoid corona discharges from said ends. So far as this latter function of the device 55 is concerned it may or may not possess the additional characteristics which provide a surge 85 proof device. Further the cross section of the shield, when considered as a corona shield, may be varied from that shown.

When operating in connection with high 90 voltages it is desirable to provide means for determining the voltage of the high tension winding by testing a fractional part of the winding, the turns of which have a known relation to the total turns of the winding. 95 I have shown in Fig. 4 a practical method of testing the high tension winding which consists of connecting one or more of the units (designated by 91) of the winding with a testing circuit 92, 93 connected to a 100 measuring device, as a volt meter, 94. In order that this testing circuit may be safely handled I may connect one side thereof to a grounded conductor 95. This method of testing the high tension winding may be 105 applied to windings specifically different from that herein shown, it only being necessary to segregate a definite fractional part of the winding, the turns of which bear a definite or known relation to the total turns 110 of the said high tension winding.

It will be understood that the structural details of the particular embodiment of my invention herein shown are capable of considerable variation within the spirit and 115 scope of the invention, and that certain of the improvements are capable of adaptation to types of transformers other than that herein shown and specifically described, and further that it is the intent to claim all of 120 inherent novelty that is disclosed in the specification and drawings.

I claim as my invention:—

1. An electrical transformer comprising a casing, a laminated magnetic circuit there- 125 in comprising a base, end pieces and a core, the latter resting on and removably sup- ported by said end pieces, said casing be-

ing provided with guides to form grooves to receive and confine the base and end members, whereby the latter are held in place with respect to each other and the 5 laminee of the members are confined solely by engagement with said guides, and transformer windings carried by the core.

2. An electrical transformer comprising a 10 casing, a laminated magnetic circuit comprising a base, end pieces and a core removably supported on the end pieces, the said end pieces abutting against the base along butt joints oblique to said members, guides in the casing walls between which the 15 laminee of the base and end members are confined and by which said members are held in place relatively to each other, and transformer windings carried by the core.

3. An electrical transformer comprising a 20 casing provided at its bottom and ends with confining guides, a laminated magnetic circuit comprising a base seated in the bottom guide and extending at its ends into the end guides and tapered at its ends, upright 25 end pieces seated in said end guides and tapered to engage the tapered ends of said base and a core resting on said end pieces, and transformer windings carried by said core.

30 4. An electrical transformer comprising a casing provided at its bottom and ends with confining guides, a laminated magnetic circuit comprising a base seated in the bottom guide and extending at its ends into the end 35 guides and tapered at its ends, upright end pieces seated in said end guides and tapered at their lower ends to engage the tapered ends of said base and a core removably supported on the upper ends of said end pieces, 40 the end pieces and core being provided, one with convexly rounded surfaces and the other with concavely rounded surface which engage to form butt joints of greater length than the width of the end pieces, and transformer 45 windings carried by said core.

5. An electrical transformer, comprising a magnetic circuit consisting of a horizontal base, upright end members and a core and transformer windings carried by the 50 core, one surrounded by the other, and spaced from each other to provide between them a longitudinal passage, and the core being inclined to the plane of the base to promote circulation of a cooling fluid through said passage.

6. An electrical transformer, comprising a magnetic circuit consisting of a base, end members and a core, and transformer windings carried by the core, one within the 60 other, the inner windings being spaced from the core and the windings being spaced from each other to provide circulating passages, and the core being inclined to the plane of the base to promote the circulation of a cooling fluid through said passages.

7. An electrical transformer comprising a magnetic circuit consisting of a base, end pieces and a core, said end pieces being convexly rounded at their upper ends and the core provided with concave recesses to receive said rounded ends of the end pieces, to thereby increase the contact at the butt joints thus formed, said core being inclined relatively to the base piece and transformer windings carried by the core and provided 75 with longitudinal oil passages.

8. An electrical transformer comprising a magnetic circuit embracing a side piece, end pieces and a core, high and low tension windings carried by the core, and two insulating shells between the high and low tension windings one of which extends slightly beyond the ends of the windings and the other of which extends beyond the 80 first shell and terminates short of the end 85 pieces of the magnetic circuit.

9. An electrical transformer comprising a magnetic circuit embracing a side piece, end pieces and a core, high and low tension windings carried by the core, and two insulating shells between the high and low tension windings, one of which extends slightly beyond the ends of the windings and the other of which extends beyond the 90 first shell and terminates short of said end 95 pieces of the magnetic circuit, there being a circulating passage between the shells for a cooling medium.

10. An electrical transformer comprising a core, a low tension winding surrounding 100 said core, means to provide between the core and the low tension winding a longitudinal oil passage, an insulating shell surrounding the low tension winding and a high tension winding surrounding said shell and spaced 105 therefrom to form an oil passage, said core being generally horizontal but slightly inclined so that one end is lower than the other to promote circulation of a cooling medium through said passages.

11. An electrical transformer comprising a core, a low tension winding surrounding the same, means to provide between the core and the low tension winding a longitudinal oil passage, two shells surrounding the low tension winding, with spacing means between them to provide a longitudinal oil 115 passage, and a high tension winding surrounding the outer shell and spaced therefrom to form an oil passage, said core being inclined, with one end thereof slightly lower than the other.

12. An electrical transformer comprising a core, a low tension winding surrounding the same, means to provide between the core and the low tension winding a longitudinal oil passage, two shells surrounding the low tension winding, with spacing means between them to provide a longitudinal oil 125 passage, a high tension winding surround- 130

ing the outer shell, spacing means between the outer shell and the high tension winding to form a longitudinal oil passage, said core being inclined relatively to the horizontal, 5 and said high tension winding being composed of a plurality of disk-like, spirally wound units and radial spacer members to provide radial oil passages between said units.

13. An electrical transformer comprising a core, high and low tension windings surrounding the core, an insulating shell between the windings, means whereby each winding is spaced from the insulating shell 5 to provide longitudinal cooling passages between the shell and the windings, each of said windings being composed of disk-like winding units with spacing members between the units to provide radial passages 20 for a cooling medium.

14. An electrical transformer comprising a core, high and low tension windings thereon, each winding composed of a plurality of disk-like winding units disposed side by side, an insulating shell between the high and low tension windings, radial spacers between the units of the windings and insulating longitudinal spacer elements between each winding and the insulating shell to 25 space the shell from said windings to provide oil passages, said longitudinal spacer elements being interlocked to the inner and outer ends of the radial spacers.

15. An electrical transformer comprising a core, high and low tension windings thereon, each winding composed of a plurality of disk-like winding units disposed side by side, an insulating shell between the high and low tension windings, radial spacers between 40 the units of the windings and insulating longitudinal spacer bars between each winding and said insulating shell, said bars being provided with undercut grooves and the radial spacers being provided with lugs to 45 interfit therewith, said lugs terminating short of the bottoms of the grooves to provide along said bottoms of the grooves longitudinal oil channels.

16. An electrical transformer comprising a core, high and low tension windings surrounding the same, the high tension winding comprising a plurality of disk-like winding units, radial spacers separating the units to provide oil passages between them, 55 and longitudinal insulating bars arranged inside and outside of the units and interlocked to the radial spacer members, whereby the units of the winding are locked together to permit the complete winding to 60 be handled as a unit.

17. In an electrical transformer, a winding composed of a plurality of spirally wound units, with means for connecting them to an outer circuit, radial spacers to 65 provide radial oil passages between the

units, and longitudinal bars inside and outside the series of units interlocked to the ends of the radial spacers, whereby the complete winding consists of a rigid unitary structure.

18. In a transformer, a core, a primary winding thereon, a secondary winding in inductive relation to the primary winding and said core, said secondary winding being composed of a plurality of separately wound coil sections having substantially flat faces which oppose and are spaced from each other, with insulating and spacing strips between them extending transversely across said faces to provide transverse ventilating passages between the sections and means arranged across the inner and outer edges of the coil sections and engaging the insulating strips to hold said strips properly spaced and to constitute inner and 80 outer ventilating passages, which communicate with said transverse passages.

19. A winding for electrical apparatus comprising a plurality of spaced, disk-like winding sections, insulating spacers between 90 them and strips extending across the inner and outer edges of said sections and interlocked to the inner and outer ends of said spacers.

20. A plurality of disk-like winding sections, each composed of a flat, bare, spirally wound wire insulated between the turns thereof, with each edge of each turn bared at the sides of the sections, transverse insulating spacers between the sections and 100 inner and outer strips arranged across the edges of the sections and interlocked to the inner and outer ends of said spacers.

21. An electrical transformer comprising a core, high and low tension windings surrounding the same, the high tension winding comprising a plurality of disk-like winding units, radial spacers separating the units to provide oil passages between the units for the circulation of a cooling 110 medium; said radial spacers being provided with longitudinal slots arranged obliquely to their planes and conductors within said slots for connecting the inner and outer turns of adjacent units.

22. An electrical transformer comprising a casing, a magnetic circuit therein composed of a base, end pieces and a core supported on said end pieces, high and low tension windings surrounding the core and 120 corona shields inclosing the base and end pieces of the circuit and curved outwardly therefrom toward the walls of the casing.

23. An electrical transformer comprising a casing, a magnetic circuit therein, embracing a core, high and low tension windings carried by the core, conductors connected to the high tension winding and extending outwardly through an insulating bushing in the casing wall, and a corona shield of 130

curved cross section surrounding said bushing between the same and the surrounding casing wall.

24. An electrical transformer comprising a core, high and low tension windings separated by insulation and corona shields at the ends of the high tension winding, said shields being formed with oppositely facing curved surfaces.

10 25. An electrical transformer comprising a magnetic circuit embracing a core, high and low tension windings, an insulating shell between said windings, said shell terminating short of the ends of the core and 15 externally curved corona shields between the high tension winding and the ends of the magnetic circuit.

26. An electrical transformer comprising a magnetic circuit embracing a core, high and low tension windings, an insulating shell between said windings, a frame supporting the magnetic circuit and braces end-

wise disposed relatively to the axes of the windings, between said frame and the high tension winding.

25

27. An electrical transformer comprising a magnetic circuit embracing a core, high and low tension windings, an insulating shell between the said windings, said shell terminating short of the magnetic circuit, 30 a frame supporting the magnetic circuit, braces between said frame and the high tension winding, and means carried by said braces and engaging said shell to hold it from shifting endwise.

35

In testimony that I claim the foregoing as my invention I affix my signature, in the presence of two witnesses, this 12th day of June, A. D. 1915.

CHESTER H. THORDARSON.

Witnesses:

W. L. HALL,
G. E. DOWLE.
